UNITED STATES PATENT OFFICE.

ARCHIBALD NEWTON WESLEY RICHARDSON, OF GLADESVILLE, NEW SOUTH WALES,
AUSTRALIA.

STIFFENING AND NECKTIE-SUPPORTING MEANS FOR SOFT AND SEMISOFT COLLARS.

Application filed December 2, 1927, Serial No. 237,280, and in Australia January 4, 1927.

This invention relates to double collars of soft or semi-soft type which when worn on the person soon lose their freshly laundered appearance owing to the tendency of the points or peaks to curl or wrinkle, this tendency being particularly evident when a necktie is worn with the collar. Furthermore there is a tendency for a necktie when worn with this type of collar, to drop unless very tightly knotted.

The object of this invention is to provide means, readily attachable and detachable, to not only stiffen the front edges of the outer fold of the collar and hold the peaks close to the shirt to which it is attached, but also to hold a necktie well up in the angle between the inner and outer folds so that it will not drop should the knot slacken.

The invention consists in a device (of which two, made respectively right and left handed, are required for each collar) of light flexible material, preferably metal such as flat wire, shaped to provide a stem and at one end a loop or eye to receive the tie.

The stem of the device is fitted in a sheath formed on the inside of the front edge of the peak of the outer fold of the collar, the sheath being parallel to and located close to said edge and open at its upper end.

The loop is of open type to permit a tie to be easily placed therein.

Reference to the accompanying drawings will clearly indicate the form and purpose of devices according to this invention and their position when in use. In the drawings:

Fig. 1 shows in elevation a collar with stiffening and tie-holding devices fitted thereto, the view presenting the inner face of the outer fold with the inner fold turned up;

Fig. 2 shows in elevation the front portion of the collar as worn, with necktie in position;

Fig. 3 is a perspective view of one end of the collar (the inner fold being turned up) with stiffening and tie-holding device;

Figs. 4 and 5 show separately the left and right hand stiffening and tie holding devices viewed from the rear;

Fig. 6 is a sectional elevation of one end of a collar taken through the sheath and

showing the stiffening and tie holding device therein.

In this figure the relative disposition of the parts is somewhat exaggerated to more clearly illustrate one effect of the use of the invention as hereinafter described.

a indicates the inner fold of the collar having the usual stud-holes *a*¹, while *b* indicates the outer fold in the front edges of which are formed the sheaths *b*¹ for the reception of the stems of the stiffening and tie holding devices. Each of these devices consists of a strip of flat metal wire shaped to provide a curved stem *c* which at one end is bent to provide an open loop *c*¹.

The portion of the wire which forms the loop is not bent in a plane but in the form of a helix as clearly shown in the drawings; and each member of a pair of devices has the helix of the loop opposite to that of the other, thus constituting right and left hand devices respectively as shown clearly in Figs. 2, 4 and 5.

The object of this helical formation of the loops is to increase the distance between them when a pair of devices are fitted to a collar thus affording greater space for the knot of the necktie *d* as shown in Fig. 2.

In fitting a necktie such as *d* to or on a collar equipped with a pair of my devices, it is laid in the loops *c* as shown by dotted lines in Fig. 1. The collar is then folded over and attached to the shirt in the usual way. The tie is then knotted and drawn as tightly as may be desired. The tension of the tie bears on the inside of the loop and tends to move it in the direction indicated by the arrow *e* in Fig. 6. This has the effect of pulling the lower end of the stem *c* inwardly thus pressing the point of the collar to the shirt.

A further advantage resulting from the use of a pair of these devices is that the angle between the inner and outer folds is held open by the loops *c*¹ (see Fig. 6) to permit the tie to slide freely.

A feature of the device is that the loop being open a tie may be readily passed thereto and does not require to be threaded through it and thereby crumpled.

By means of these simple devices a soft or semi-soft collar is prevented from curling at the points which are held closely to the shirt.

front, and a necktie is prevented from dropping should the knot become slack.

What I claim and desire to secure by Letters Patent is:—

- 5 1. Collar-stiffening and necktie-supporting means consisting of a strip of material shaped to provide a slightly curved stem and at one end an open loop to receive a tie.
2. Collar-stiffening and necktie-supporting

means consisting of a strip of material, portion of which constitutes a stem to fit in a sheath formed along the front edge of the outer fold of a collar, while another portion is helically bent to constitute an open loop to receive a tie.

Signed at Sydney, New South Wales, this third day of November, A. D. 1927.

ARCHIBALD NEWTON WESLEY RICHARDSON.
